PENHOLDER

Pearson Chapman, Washington, D. C.; American Security and Trust Company executor of said Pearson Chapman, deceased

Application February 25, 1937, Serial No. 127,785

7 Claims. (Cl. 120—101)

This invention relates to new and useful improvements in the general art of stationery and more particularly to a novel form of pen holder.

The principal object of this invention is to provide a pen holder adapted to hold pen points of various sizes and cross sectional formations.

Another important object of the invention is to provide a pen holder which will not only accommodate pen points of various size and formation, but which will firmly grip the pen to prevent wobbling and accidental displacement thereof from the holder.

Still another important object of the invention is to provide a pen holder which will not only firmly grip pen points of various characteristic formations, but which will also permit immediate release of the pen point when desired.

These and various other important objects and advantages of the invention will become apparent to the reader of the following specification.

In the drawing:—

Figure 1 represents a fragmentary longitudinal sectional view through the pen holder showing a pen point in held position.

Figure 2 is a side elevational view fragmentarily showing the pen holder with the holding means in released position.

Figure 3 is an enlarged end elevational view of the holder.

Figure 4 is a longitudinal sectional view through the sleeve.

Referring to the drawing wherein like numerals designate like parts, it can be seen that numeral 5 denotes the usual shank of the holder which in the present instance is reduced at one end portion to accommodate the ferrule 6 from which projects the pin 7.

This end portion of the shank 5 is provided with a longitudinally extending opening axially disposed, for receiving the shank portions 8 and 9 of the spring fingers 10 and 11, respectively, as well as the inner end portion of the elongated core member 12, which core member is preferably of polygonal cross-sectional shape.

As is clearly shown in Figure 1, the outer end portion of the core member 12 is interposed between the fingers 10—11 and at its extremity is beveled as at 13.

The finger 10 is provided with the laterally diverged portion *a* merging with the inwardly disposed T-formation *b*.

The outer end of the finger 11 is diverged laterally as at *c* and is provided with the inwardly disposed and transversely extending arcuate-shaped yoke 14.

As shown in Figure 1, numeral 15 denotes a standard type of pen point. In properly placing the pen point 15, the blunt end thereof is interposed between the brace extension 16 on the finger 11, and the outer end portion of the core member 12, this portion of the core member 12 preferably being wholly confined within the channel of the pen point.

Now referring to the slidable sleeve 17, it can be seen that this sleeve is provided with a pocket-like construction 18 at its inner end, the forward edge portion of which is disposed and formed to define a cam surface 19 for riding engagement with the pin 7. Obviously when this sleeve 17 is rotated toward the right (see Figure 2) the cam surface 19 in riding against the pin 7 will cause longitudinal movement of the sleeve in a direction toward and against the fingers 10—11. Riding engagement of the sleeve against these fingers 10—11 will cause the fingers to contract, bringing the arcuate-shaped yoke 14 into engagement with the convex side of the pen point and bringing the T-shaped formation *b* into bridging engagement with the channeled side of the pen point.

It will be observed, that the yoke 14 with the cooperation of the brace formation 16 will firmly clamp the pen point against the core member 12. At the same time the T-shaped formation reinforces the pen point to prevent any objectionable deformation thereof.

The sleeve 17 may be provided with the usual cork or other suitable covering.

While the foregoing specification sets forth the invention in specific terms, it is to be understood that numerous changes in the shape, size and materials may be resorted to without departing from the spirit and scope of the invention as claimed hereinafter.

Having described the invention what is claimed is:—

1. In a pen point holder including a shank, a pair of shank attachable fingers at one end of the shank, and means for contracting said fingers against opposite side portions of a pen point, and a brace formation extending longitudinally of the fingers and adapted to bear against the convex side of a pen point at the shank end thereof.

2. In a pen point holder including a shank, a pair of shank attachable fingers at one end of the shank, and means for contracting said fingers against opposite side portions of a pen point, one of said fingers having a T-head formation bridging the channeled side of a pen point.

3. A pen holder comprising a handle part, a core member projecting from one end thereof and adapted to fit in the channel of a pen point, a pair of spring fingers connected with said end of the handle and arranged one above the core member and one below said member, said fingers having parts extending toward each other for gripping a pen point between them and for pressing portions of the point against the core member.
4. A pen holder comprising a handle part, a core member projecting from one end thereof and adapted to fit in the channel of a pen point, a pair of spring fingers connected with said end of the handle and arranged one above the core member and one below said member, said fingers having parts extending toward each other for gripping a pen point between them and for pressing portions of the point against the core member, and a sleeve slidably arranged on the handle and engaging the spring fingers for pressing the fingers toward each other when the sleeve is moved outwardly on the handle.
5. A pen holder comprising a handle, a core member projecting from one end thereof, a pair of spring fingers connected with said end of the handle and arranged one above and one below the core member, the upper member having a laterally inwardly extending yoke-shaped part for engaging a portion of the convex side of a pen point, the concave side of which engages the core member and the other spring finger having an inwardly extending extremity having a straight edge for engaging the edges of the pen point and a sleeve slidably arranged on the handle and pressing the spring fingers against the point when the sleeve is moved outwardly.
6. A pen holder comprising a handle, a core member projecting from one end thereof, a pair of spring fingers connected with said end of the handle and arranged one above and one below the core member, the upper member having a laterally inwardly extending yoke-shaped part for engaging a portion of the convex side of a pen point, the concave side of which engages the core member and the other spring finger having an inwardly extending extremity having a straight edge for engaging the edges of the pen point and a sleeve slidably arranged on the handle and pressing the spring fingers against the point when the sleeve is moved outwardly.
7. A pen holder comprising a handle, a core member projecting from one end thereof, a pair of spring fingers extending from said end of the handle, one above and one below the core member, the upper finger having an inwardly extending extremity of yoke-shape for pressing against a portion of the convex side of the pen point and said finger having an extension intermediate its ends for pressing the inner end of the point against the core member, the extremity of the other finger having an inwardly extending part formed with a straight edge for bearing against the edges of the point and means for pressing the spring fingers toward each other to cause them to grip the point.
